UNITED STATES PATENT OFFICE.

FRANCISCO JACINTO DEL CORRAL, OF PHILADELPHIA, PENNSYLVANIA, AS-
SIGNOR TO THE ENTERPRISE MANUFACTURING COMPANY OF PENNSYL-
VANIA, OF SAME PLACE.

DESIGN FOR A BUNG-HOLE BORER.

SPECIFICATION forming part of Design No. 29,024, dated July 12, 1898.

Application filed April 28, 1898. Serial No. 679,145. Term of patent 14 years.

To all whom it may concern:

Be it known that I, FRANCISCO JACINTO DEL CORRAL, a citizen of the United States, residing in Philadelphia, Pennsylvania, have invented a certain new and useful Design for Bung-Hole Borers, of which the following is a specification.

My design for a bung-hole borer is clearly illustrated in the accompanying drawing, the figure in which shows the borer in perspective.

The leading feature of the design is the shank, having a head with three extensions, the central extension being tapered and screw-threaded and the outer extensions being shaped as shown.

A is a shank having a head A', with three

extensions a a' a'. The central extension a is tapered and has a screw-thread at its end. The other two extensions a' a' project down 20 on each side of the center prong and are shaped as shown. The upper portion of the shank has an enlargement a².

I claim—

The design for a bung-hole borer as herein 25 described and as shown in the accompanying drawing.

In testimony whereof I have signed my name to this specification in the presence of two subscribing witnesses.

FRANCISCO JACINTO DEL CORRAL
